ATTORNEYS,

UNITED STATES PATENT OFFICE.

JAMES E. EMOND, OF BELEN, NEW MEXICO.

HEEL-FILLER BLOCK.

1,395,804.

Specification of Letters Patent.

Patented Nov. 1, 1921.

Application filed December 2, 1920. Serial No. 427,828.

To all whom it may concern:

Be it known that I, JAMES E. EMOND, a citizen of the United States, residing at Belen, in the county of Valencia and State 5 of New Mexico, have invented new and useful Improvements in Heel-Filler Blocks, of which the following is a specification.

My present invention pertains to railway track construction, and it contemplates the 10 provision of a heel filler for railroad switch points that is easily and quickly applied and as readily replaced with a new filler when occasion demands.

The invention further contemplates the 15 provision of a heel filler that will leave the main rail free at all times due to the fact that the heel fits up under the ball of the rail against the web thereof and when properly positioned the heel answers as an outer 20 side angle bar at the joint where the switch point and lead rail connect. The device also acts as a safety block at the heel of the switch.

The invention in all of its details will be 25 fully understood from the following description and claims when the same are read in connection with the drawings, accompanying and forming part of this specification, in which:

30 Figure 1 is a top plan view of a portion of the lead rail and a portion of the switch point secured together and showing my novel heel filler block secured thereto. The main line rail is not illustrated.

35 Fig. 2 is a side elevation of Fig. 1.

Fig. 3 is a perspective view of the filler.

Fig. 4 is a longitudinal section of the filler.

40 Fig. 5 is a cross-section taken slightly in rear of the abutting ends of the lead rail and switch point and showing the lead rail and filler block secured thereto.

Fig. 6 is an elevation of one end of the 45 filler and Fig. 7 an elevation of the beveled end of the filler.

Fig. 8 is a top plan view of the main line rail and lead rail together with the switch point and showing my novel block secured to the lead rail and switch point 50 and resting under the head of the main line rail.

Similar numerals of reference designate corresponding parts in all of the views of the drawings.

55 My novel filler 1 is preferably provided with the cut off corners as shown to accom-

modate it to the base of opposing rails, and the said filler is also provided on its upper surface with a longitudinal groove 2, and in practice the filler bears at one side under 60 the ball of the main line rail but is not secured to the main line rail in any manner and hence free running of the main line rail with respect to the filler is permitted.

The said filler 1 is provided at equidistant points in its length with chambers or daps 3 and formed in the chambers are bolt receiving apertures 4 for the passage of bolts 5. The bolts 5 secure the filler block 1 to the web of the lead rail 9 and 65 switch point 11 and manifestly casual displacement of the bolts from the lead rail 9 and switch point 11 is prevented by the nuts 6. As shown in Fig. 5 the well known fish plate 7 is provided and bears against 70 the web of lead rail 9. The fish plate also bears against the web of the switch point 11 at the opposite side to that against which the filler block bears and hence the filler may be said to form the additional function of a fish plate on one side of the lead rail 9 and switch point 11. The bolts 5 are also employed to secure the fish plate 7 to the lead rail 9 and switch point 11. 80

As shown in Figs. 1 to 4 of the drawings I provide the filler with the beveled end 10.

It will be gathered from the foregoing that the device is very simple in construction and inexpensive to produce and the 90 expense of drilling may be saved, and this is due to the fact that the filler commonly employed is secured not only to the lead rail, and switch point but also to the main line rail, whereas my filler is not attached to the main line rail but to the lead rail and switch only. Manifestly this will eliminate drilling of the main line rail and will permit of running thereof with respect to the lead and switch. 95

In attaching heels in common use it is necessary to employ a bolt twice as long as the present railway bolt. However with my device the ordinary well known bolt may be employed.

When a railway switch is provided with my novel filler, the main line rail may run free without kinking at the heel of the switch point. Moreover the wing frogs will not stand open and at the same time I 110 eliminate re-drilling of hot rails or the running thereof.

Having described my invention, what I claim and desire to secure by Letters-Patent, is:—

1. In railway track construction the combination of a main line rail, a lead rail arranged adjacent thereto, a switch point abutting at one end against one end of the lead rail, and a filler interposed between the main line rail and said lead rail and switch point and unattached to the main rail, equidistant channels formed in the filler and extending from the upper surface thereof to the side in close proximity to the lead rail and switch point, and means adapted to pass through the chambers for securely retaining the filler with respect to the lead rail and switch point.
2. In track construction, the combination of a main line rail, a lead rail and switch point arranged parallel with respect to the main rail and having abutting ends, and a filler removably secured to the side of the

lead rail and switch point and having a portion of its surface resting against the web of the main rail unattached thereto.

25

3. In track construction the combination of a main line rail, a lead rail and switch point having abutting ends and running in the same plane parallel to the main line rail and a filler secured to the lead rail and switch point and unattached to the main rail; said block having rounded corners adapted to rest against the webs of the rails and switch point and further having chambers therein that extend from the upper face of the filler to one side wall thereof.

30

35

In testimony whereof I have hereunto set my hand in presence of two subscribing witnesses.

JAMES E. EMOND.
